UNITED STATES PATENT OFFICE.

HAZEL B. BUSH, OF REDLANDS, CALIFORNIA, ASSIGNOR TO THE BUSH ELECTRIC COMPANY, OF CLEVELAND, OHIO, A CORPORATION OF OHIO.

HOT-WIRE CUTTER.

Application filed April 5, 1919. Serial No. 287,801.

To all whom it may concern:

Be it known that I, HAZEL B. BUSH, a citizen of the United States, residing at Redlands, in the county of San Bernardino and 5 State of California, have invented a certain new and useful Improvement in Hot-Wire Cutters, of which the following is a full, clear, and exact description, reference being had to the accompanying drawings.

10 This invention relates to an instrument for cutting and handling charged electric wires, examples of its use being to cut, and remove if desired, insulator tie wires of high voltage lines while current prevails in 15 the lines; and to snip service wires leading from high power lines while such lines are "hot" or charged with electricity.

Objects are to provide an instrument by means of which heavily charged electric 20 wires may be cut with ease and safety; or by means of which auxiliary wires, such as tie wires, that are twisted about main lines may be cut completely therefrom without danger of cutting or injuring the main line; 25 to provide an instrument of the aforesaid character that is very strong and durable; that is so constructed as to materially increase the power applied to its operating member during transmittal to the cutting 30 elements; and to equip the instrument with adjustable means for adapting it to the cutting of wires of different diameters or gauges.

The foregoing objects and others which 35 will become apparent as this description proceeds are attained in the construction illustrated in the drawing accompanying and forming a part hereof and wherein Fig. 1 is a perspective view of the instrument 40 illustrating the manner in which it is used; Fig. 2 is a sectional side elevation of the instrument; Fig. 3 is a section at right angles to Fig. 2; Fig. 4 is an enlarged detail showing the reverse side of parts revealed 45 in the sectional view of Fig. 2; and Fig. 5 is a modification of the gauge.

The handle 1 of the instrument or cutter is, in the present instant, made up of side members 2 that are spaced apart at their lower ends, by an insert 3, a distance substantially equal to the width or thickness of slide 4 that is reciprocable between the side members 2 and is adapted to be shifted or reciprocated by mechanism involving the 50 lever 5 and enclosed within a casing 6 that

is applied to the handle. The lever is pivoted on a pin 7 extending through the sides of casing 6 and the lever has connection, through links 8, with the lower end of slide 4. As these parts do not enter into 60 my present invention, further description and illustration is deemed unnecessary.

Turning now to the cutting mechanism that is situated at the end of the handle remote from lever 5, what I may term a 65 "stationary jaw" 10 has its inner end secured, as by bolts 11, within a casing 12 that is applied to the handle 1 and attached to the side members 2 thereof by fastening means 13. Guides 15 extend along the edge 70 portions of one side of the inner end of jaw 10 and the same are shown as held in place by the above mentioned bolts 11. Operating between these guides is a head 16 that has its lower end connected to slide 4. The connection may be made by reducing the thickness of the lower end of the head and engaging it with the incut side of slide 4 so that the extreme end of the head bears upon a shoulder of the slide. A plate 18 is like- 75 wise applied to the opposite incut side of the slide and the parts are secured together by rivets 17. Where plate 18 projects above the slide it is fastened to head 16, as by rivets 19. Thus it will be seen that a connection is made between the slide and head 80 capable of withstanding a very heavy thrust. 85

A movable jaw 20 is pivoted as by means of a substantial rivet 21, to the stationary jaw 10. The lower end of the movable jaw 90 has pivotal connection, through a pin 22, with one end of a link 23, while the opposite end of the link has similar connection through a correspondingly numbered pin, with the upper end of head 16. To relieve the pivot pins 22 of the shearing stresses that would otherwise be imposed upon them, I insert between the opposed ends of the head and jaw a thrust plate 24 which is carried by the link and may, so far as principle is concerned, be regarded as an integral part thereof. The ends of the thrust plate and parts against which they bear are curved concentric with the pivot pins 22. 95

The upper ends of the jaws 10 and 20 are 105 provided with notches 25 that are sufficiently large to receive the maximum gauge wire which the instrument is designed to cut.

A gauge 27 in the form of a plate is pivoted to the outer side of each jaw, in the 110

present instance on the same pivot or rivet 21 through which the jaws are connected. These plates are substantially identical and their upper edges are notched at 28 to different depths. By turning the gauge plates to bring their corresponding notches into register with notches 25 of the jaws, the effective depths of the notches 25 may be made to correspond substantially to the diameter of a wire the gauge whereof is represented by the particular notches 28 selected. As a convenient means of retaining the gauge plates in any adjusted position, I have shown each as provided with an arcuate slot 30, concentric with the pivotal axis of the plate, and through which a screw 31 extends and is threaded into the adjacent jaw. By loosening the screw, the plate may be freed and thereafter turned to any desired position, and by then tightening screw, the plate may be securely held against displacement. For convenience I have provided each gauge plate with indications 32 which designate the gauges within the scope of the plate, and the jaw wherewith the plate is associated, with an index 33 for cooperation with the indications.

It is obvious that instead of making the plates notched at their upper ends, the same may be made with their upper edges curved on an arc eccentric to the pivotal axes of the plates, and by adjusting the plates angularly with respect to the jaws, they may be caused to cover to a greater or less extent the lower portions of the notches of the jaws. Such a modification is illustrated in Fig. 5 where the plate is designated 27^a, and its curved upper edge, 28^a.

The operation of the instrument will be readily understood from the foregoing description. However, it may be related briefly that when it is desired, for example, to cut a tie wire of given gauge from a line wire, in the act of doing which the instrument is shown in Fig. 1, the operator adjusts the gauge plates 20 according to the gauge of the tie wire and, at a safe and convenient distance from the wire, applies the cutter to the tie wire T and draws down on the lever 5 which will result in pushing the slide 4 upward and elevating the head 16 to operate the movable jaw and shear or snip the wire. When the tie wire has thus been severed, the parts may be untwisted and pulled from the line wire L by the use of my instrument. In such an operation the jaws are forced together with sufficient pressure to securely grasp but not cut the wire.

It will be readily seen that injury to the line wire is rendered impossible by the gauge plates preventing the cutting jaws from coming in contact with the line wire.

The elements of handle 1 and the slide 4 are of insulating material, preferably wood especially treated for the purpose, so that

the operator is in no danger of getting shocked through his using the instrument.

Having thus described my invention what I claim is:—

1. An instrument of the character set forth comprising a handle, a jaw carried by the handle, a second jaw pivoted to the first jaw, said jaws having cooperating cutting parts, a head, opposed guides between which the head is slidable, a link having its opposite ends pivotally connected respectively to the second jaw and head, a thrust element carried by the link and interposed between the head and second jaw, the bearing surfaces of the thrust member and the surfaces of the second jaw and head that engage therewith being curved on arcs concentric with the pivotal connections between the aforesaid link and the second jaw and head, a slide wherewith the head is connected, and means for reciprocating the slide.

2. An instrument of the character set forth, comprising a pair of cutting elements movable with respect to each other, the elements having notches which register when the elements are in normal relation to each other, means for creating relative movement between the elements, and means for varying the effective depth of the aforesaid notches.

3. An instrument of the character set forth comprising a pair of cutting elements movable with respect to each other, the elements having notches which register when the elements are in normal relation to each other, means for creating relative movement between the elements, a gauge plate movably carried by one of said elements and having a part arranged to extend a greater or less extent over the notch of said element when the plate is moved with respect to the element, and means for holding the plate in any adjusted position.

4. An instrument of the character set forth comprising a pair of cutting elements movable with respect to each other, the elements having notches which register when the elements are in normal relation to each other, means for creating relative movement between the elements, a gauge plate pivoted to each element and having an edge portion adjacent the notch of such element, said edge portion being graduated to cover or uncover said notch to a greater or less extent as the plate is swung upon its pivot, and means for retaining the plate in any adjusted position.

5. An instrument of the character set forth, comprising a pair of cutting elements movable with respect to each other, the elements having notches which register when the elements are in normal relation to each other, means for creating relative movement between the elements, a gauge plate movably carried by one of said elements, said gauge plate having notches of varying depths that are adapted to be brought into register with

the notch of the element, and means for securing the plate in any adjusted position with respect to the element.

6. An instrument of the character set forth comprising a pair of jaws, means pivotally connecting the jaws, the jaws having notches which register with each other when the jaws are in normal condition, a gauge plate pivoted upon the aforesaid pivotal means and having notches of varying depths that are adapted to be placed individually in register with the notch of the adjacent jaw, and means for locking the plate in any adjusted position.

15 7. An instrument of the character set forth comprising a pair of jaws, means pivotally connecting the jaws, the jaws having notches which register with each other when the jaws are in normal condition, a gauge plate pivoted upon the aforesaid pivotal means adjacent each jaw, each gauge plate having notches of varying depths that are adapted to be placed individually in register with the notch of the corresponding jaw, the plate having an arcuate slot concentric with the pivotal axis of the plate, and means extending through the slot and threaded into the jaw for locking the plate in any adjusted position.

25 8. An instrument of the character set forth comprising a pair of relatively movable jaws, means for creating relative movement between the jaws, the jaws having notches which register with each other when the jaws are in normal condition, a gauge as-

sociated with one of said jaws, said gauge being adjustable to vary the effective depth of the notch of said jaw, the jaw and gauge having cooperating indications, and means for securing the gauge in any adjusted position.

40 9. An instrument of the character set forth comprising a pair of jaws, means pivotally connecting the jaws, the jaws having notches which register with each other when the jaws are in normal condition, a gauge plate pivoted upon the aforesaid pivotal means adjacent each jaw, each gauge plate having notches of varying depths that are adapted to be placed individually in register with the notch of the corresponding jaw, the plate having an arcuate slot concentric with the pivotal axis of the plate, means extending through the slot and threaded into the jaw for locking the plate in any adjusted position, each plate having indications, and the corresponding jaw index mark for cooperation with said indications.

45 10. An instrument of the character set forth, comprising a pair of cutting elements movable with respect to each other and having cooperating cutting parts, means for creating relative movement between the elements, and adjustable means for covering or uncovering to a greater or less extent the cutting parts of said elements.

50 55 In testimony whereof, I hereunto affix my signature.

HAZEL B. BUSH.
